C. S. SWIFT.
WINDOW STOP.
APPLICATION FILED NOV. 8, 1915.

1,174,101.

Patented Mar. 7, 1916.

UNITED STATES PATENT OFFICE.

CHARLES S. SWIFT, OF NEW YORK, N. Y.

WINDOW-STOP.

1,174,101.

Specification of Letters Patent. Patented Mar. 7, 1916.

Application filed November 8, 1915. Serial No. 60,216.

To all whom it may concern:

Be it known that I, CHARLES S. SWIFT, a citizen of the United States, and a resident of New York city, borough of Manhattan, in the county of New York and State of New York, have made and invented certain new and useful Improvements in Window-Stops, of which the following is a specification.

10 This invention relates to a locking mechanism for windows, the object of the invention being to provide a simple but effective device of this class which will lock the upper and lower sashes of a window against 15 opening beyond a certain limit, and wherein the locking mechanism is of neat and simple appearance, comprehending but few parts, and of such design and arrangement as to not in any way mar or detract from the 20 slightly appearance of the window to which it is secured.

A further object is to provide a locking mechanism adapted to accomplish the aforementioned ends, wherein the mechanism is 25 so arranged that it may be applied with equal facility to windows either in the course of construction or to those already completed.

30 A further object is to provide a locking mechanism which may be swung from its operative position and when so located does not in any way interfere with the free opening and closing of the window sashes, being held out of contact therewith. The locking 35 mechanism is further so arranged that, when in its operative position, it is positively held in such location, so that there is no danger or likelihood of maliciously inclined people releasing the locking mechanism either when 40 the sashes are partially raised and in their partially open positions, or when the sashes are entirely closed.

Other objects and advantages will appear as the description proceeds, wherein it is to 45 be understood that changes in the precise embodiment of the invention, and with regard to proportions and minor details, may be made without departing from the spirit of the invention.

50 The preferred embodiment of my invention is disclosed in the accompanying drawing, wherein:

Figure 1 is a fragmental view in perspective of a window comprising upper and 55 lower sashes, and to which my novel window locking mechanism is applied, the sashes be-

ing illustrated in their open and limited positions, and held against further opening by the locking mechanism; Fig. 2 is a detailed view of the locking mechanism, and 60 brings out the simplicity of the same, as well as clearly illustrating the fact that but little labor and material are necessary for its manufacture; Fig. 3 is a view in side section of the locking mechanism and illustrating the pivotal securement of the locking frame to the supporting base; Fig. 4 is a view in front elevation of the lower portion of the upper sash, the same being equipped with a runway plate, with which 65 the pivoted frame of the locking mechanism is adapted to engage; Fig. 5 is a view in section, taken on the line 5—5 of Fig. 4; Fig. 70 6 is a view in section taken on the line 6—6 of Fig. 4; and Fig. 7 is a fragmental view 75 of a slightly modified form of runway plate.

Referring specifically to the several views, the window-frame 10, including the stiles 11, is provided with the upper and lower window sashes 12 and 13, respectively, and, 80 as thus outlined, represents the conventional type of window. The upper sash 12 is formed with the side rails 14, and the parting rail 15. The lower sash includes the side rails 16 and the parting rail 17, it being to 85 these side and parting rails of the sashes that my improved locking mechanism is adapted to engage and limit the degree to which the window sashes may be opened.

The locking mechanism is formed with 90 the supporting base 18, through which extends suitable openings 19 for the reception of holding screws, and by means of which latter the base is rigidly secured to the stile 11 of the window-frame, and at a point directly opposite the position of the parting rails, when the window sashes are in their closed positions. The base is formed with the overhanging loop 20, through which and through the base extend the aligned openings 95 21 for the fixed reception of a pin 22, which acts as a pivotal mounting for a locking frame 23.

The locking frame, which is, for economical reasons, preferably formed from a single 100 piece of metallic rod, is substantially U-shaped, and is formed with the spaced arms 24—25, which are connected at their one extremities by the cross member or stop 26. The arm 24, which acts as a supporting arm, 110 is pivoted at its lower extremity 27 to the base 18, so that the entire locking frame

may swing into the raised and operable position, illustrated in Fig. 1, or may assume a lowered position by swinging outwardly and downwardly in the direction, as indicated by the arrow "A" in Fig. 1. In this connection, it is to be noted that the opening in the arm 24 of the locking frame, through which the pivot pin 22 extends, is positioned to one side of the longitudinal center of the said arm, so that the arm 24 is limited to a vertical position when swung downward by the upper edge 24' of the supporting arm contacting with the inner surface 20' of the overhanging loop, which thus holds the arm spaced away from the side rail of the window sash.

The spacing of the arms 24-25 is slightly greater than the width of the parting rail 17 of the lower sash, so that it may be contained therein, and be restricted in its movement while so positioned by the cross member or stop 26. The free arm of the locking frame 23 is provided at its lower extremity with the outwardly turned neck 27', which enlarges at its outer extremity to form the head 28, the connection between the head and neck defining the ledges or shoulders 29. The side rail 14 of the upper sash is provided adjacent its lower extremity with the runway plate 30, preferably countersunk therein, and thus extending flush with the outer surface thereof. The runway plate, as indicated by its name, is provided with the slot or runway 31 extending longitudinally thereof, the length of which determines the degree or extent to which the upper sash may be lowered and opened. The runway or slot 31 is of restricted width, so as to nicely receive the neck 27' of the locking frame therein. The lower extremity of the slot communicates with the wide recess 32 which is of such width that the head 28 of the locking frame may pass therethrough. As the locking frame is swung into its raised and operative position, the passage of the head of the locking frame through the recess 32 brings the neck thereof into alinement with the slot or runway 31, allowing the upper sash with the runway plate to be lowered, the shoulders or ledges 29 contacting with the rear side edges of the slot 31, and thus preventing the locking frame from becoming detached from the runway plate while the upper sash is in an open position. In this connection, it is to be noted that the upper sash is provided with a slot or channel 33, allowing for the free passage of the head behind the runway plate.

With the locking mechanism so constructed, it will be readily apparent that the locking frame is held in its operative position by either or both the upper and lower window sashes, when the same are in their open position, so that the locking mechanism can-

not be released until both window sashes have been closed, the arm 25 of the locking mechanism preventing the releasement of the locking mechanism when the lower window sash is raised, and the head 28 and the runway plate 30 preventing the releasement of the locking frame when the upper window sash is open.

In order to prevent the locking mechanism from being maliciously swung or moved from its operative position when the window sashes are closed, as might be accomplished by the insertion of a thin instrument between the parting rails, I provide a pawl 34, which is resiliently forced across a portion of the recess 32 by the spring 35. This pawl is pivoted at its outer extremity 36, and moves within a chamber 37 provided therefor. The pawl is thus properly housed, and does not interfere with the free movement of the upper and lower sashes. The head 28 of the locking frame is pointed and beveled, so that, as it strikes against the spring-pressed pawl 34, it moves the same to one side, allowing the head to pass through the wide recess 32, after which time the pawl moves across and partially closes the said recess and prevents the accidental or malicious withdrawal of the head therethrough. It will, therefore, be apparent that no amount of shaking or manipulation of the window sashes can jar the locking frame from its operative position, as it is necessary to first move the spring-pressed pawl from its locking position.

The form of runway plate illustrated in Fig. 7 is provided with the elongated recess 32', of sufficient length so that the arms 24-25 do not have to be contracted prior to their being swung outwardly. In this form of runway plate, a single spring 40 is rigidly secured to the runway plate and acts as a resilient pawl, so as to prevent the head 28 of the locking frame accidentally swinging in an outward direction and becoming detached from the runway plate.

What I claim is:—

1. A locking mechanism for windows comprising a frame; means for pivotally securing the same to the window frame, said frame including an upwardly extending arm projecting above the parting rail of the lower sash when the latter is in its lowermost position; a cross member carried by said arm and spaced a distance above said parting rail and limiting the movement thereof; means carried by the upper sash and said cross member holding said cross member in position above the parting rail of the lower sash and allowing said upper sash restricted movement.

2. A locking mechanism for window sashes, comprising a supporting base adapted to be supported to a window frame, adjacent the parting rails of the upper and

lower sashes, a frame pivotally secured to said base and including an upwardly extending arm projecting a distance above the parting rail of the lower sash when 5 the latter is in its closed position, the upper extremity of said arm projecting across the said parting rail of the lower sash and confining said lower sash to restricted movement; a runway plate carried by the upper 10 sash and means carried at the extremity of said arm detachably engaging said runway plate and confining the upper sash to restricted movement.

3. A locking mechanism for window 15 sashes, comprising a supporting base adapted to be supported to a window frame, adjacent the parting rails of the upper and lower sashes, a frame pivotally secured to said base and including an upwardly extending arm projecting a distance above the parting rail of the lower sash when the latter is in its closed position, the upper 20 extremity of said arm projecting across the said parting rail of the lower sash and confining said lower sash to restricted movement; a runway plate carried by the upper sash and means carried at the extremity of said arm detachably engaging said runway plate and confining the upper sash to restricted movement; means carried by said 25 arm holding the said frame against pivotal motion and detachment from said upper and lower sashes, when said upper and lower sashes are in their open position.

35 4. A locking mechanism for window sashes comprising a supporting base, a U-shaped frame pivotally secured thereto, said U-shaped frame including downwardly extending spaced arms with a cross member 40 extending therebetween, said frame adapted to swing above the parting rail of a window sash and receive the same between the spaced arms thereof, and co-acting means carried by the free arm of said frame 45 and the upper window sash, limiting the movements of the said upper window sash, and holding said cross member in position above the lower sash.

5. A locking mechanism for window 50 sashes comprising a base plate adapted to be secured to the side of a window frame and opposite the parting rails of the window sashes, a U-shaped frame pivotally secured to the said base and adapted to swing 55 above the parting rail of the lower sash, and to receive the same between the spaced arms of the U-shaped frame; means carried

by the free extremity of one of said arms adapted to engage the upper window sash and to restrict the movements thereof, an 60 overhanging loop carried by said base and adapted to hold the U-shaped frame when in its lowered position out of contact with the side rail of the lower window sash.

6. A locking mechanism for window 65 sashes comprising a base, a U-shaped frame pivoted at the lower extremity of one of the spaced arms of said frame to said base, the top of said U-shaped frame adapted to form a stop and limit the upward movement of 70 the lowered sash, the free arm of said U-shaped frame provided at its lower extremity with an outwardly projecting restricted neck and a wedge-shaped head carried thereby, a runway plate with a longitudinally extending slot and a widening recess communicating therewith, adapted to be secured to the upper window sash and to be engaged by the head and restricted 75 neck of said U-shaped frame. 80

7. A locking mechanism for window sashes comprising a base, a U-shaped member pivoted at the lower extremity of one of the arms thereof to said base, a restricted neck and enlarged head carried at 85 the corresponding extremity of the other of the arms of said U-shaped frame, a runway plate adapted to be secured to the upper window sash and provided with a longitudinally extending slot widening at its 90 lower extremity, the said widening portion of said slot adapted to receive the said head therethrough and a pawl mounted in front of the widening portion of said slot and adapted to prevent the withdrawal of 95 the said head.

8. A locking mechanism comprising a locking frame, means for mounting the same for pivotal motion adjacent the parting rails of a window, a slotted runway plate 100 adapted to be secured to one sash of a window, the lower portion of said runway plate provided with an enlarged recess, and a pawl carried by said runway plate and extending across the enlarged recess and 105 adapted to engage the locking frame.

Signed at New York borough of Manhattan in the county of New York and State of New York this 4th day of November A. D. 1915.
